FOREIGN PATENT DOCUMENTS

JP 1509220 S 10/2014

Primary Examiner — Selina Sikder(74) *Attorney, Agent, or Firm* — McGinn IP Law Group, PLLC(57) **CLAIM**

The ornamental design for a light emitting diode, as shown and described.

DESCRIPTION

FIG. 1 is a front perspective view of a light emitting diode showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof; and,

FIG. 9 is an alternate front view thereof wherein the lighting emitting surfaces are translucent.

1 Claim, 9 Drawing Sheets(56)
